UNITED STATES PATENT OFFICE.

LEWIS H. SELDEN, OF MINNEAPOLIS, MINNESOTA.

FIREPROOF WINDOW.

1,071,357.

Specification of Letters Patent. Patented Aug. 26, 1913.

Application filed June 3, 1910. Serial No. 564,884.

To all whom it may concern:

Be it known that I, LEWIS H. SELDEN, of Minneapolis, Hennepin county, Minnesota, have invented certain new and useful Improvements in Fireproof Windows, of which the following is a specification.

The object of my invention is to provide a fireproof window having a sash frame that is capable of adjustment with respect to the window sash, and a particular object of the invention is to provide an adjusting means easily accessible and operable to obtain the desired adjustment when the frame and the sash have been assembled.

Further objects of the invention will appear from the following detailed description.

The invention consists generally in various constructions and combinations, all as hereinafter described and particularly pointed out in the claims.

In the accompanying drawings forming part of this specification, Figure 1 is a perspective view of a portion of a window frame and sash embodying my invention, Fig. 2 is a horizontal, sectional view illustrating the adjustable portion of the frame and the means for operating it, Figs. 3 and 4 are detail sectional views of the adjusting mechanism, Fig. 5 is a detail view of the locking plate by means of which the independent outward movement of the adjusting screw is prevented.

In the drawing, 2 represents the window or sash frame composed of sheet metal having the sash weight pockets 3 and 4 separated by a division plate 5. This frame as indicated, is formed of one piece of metal and on each side of the sash shoulders 6 are formed in the metal to bear on the surface of the wall. The metal forming the shoulder 6 is bent inwardly to form flat faces 7 in planes at right angles substantially to the plane of the window sash and these faces terminate in inwardly turned flanges 8 having outwardly turned ends 9.

10 represents a plate sometimes designated as a "pulley stile", having outwardly turned vertical edges 11 which lap by the ends 9 on each side of the sash, as indicated in Fig. 1, but without being attached to these ends. A parting bead 12 is formed on the pulley stile near the middle thereof and separates the sash 13 from the one on the other side of the stop. The pulley stile is

movable for the purpose of fitting the sash in the window, or for subsequent adjustment, and is provided with strengthening bars 14 and a screw bolt 15 which passes through the hollow parting bead 12 and into a threaded socket in a bar 16 that is secured at its ends to the shoulders 6, and extends transversely of the frame between the pulley stile and the sash weight pockets, as shown clearly in Fig. 2. The bar 14 has a hole 17 therein in which a screw bolt 15 is movable and by rotating this screw the pulley stile may be moved back and forth toward and from the window sash, until the desired adjustment is obtained. The bead 12 has a hole 18 therein through which access may be had to the screw bolt with a screw driver. It is evident, however, that if the screw bolt be rotated without some means for preventing its longitudinal movement with respect to the pulley stile, that no adjustment of the stile could be obtained. I therefore provide a locking plate 19 movable in guides in the bead 12 and having holes 20 accessible through a slot 21 in said bead and a larger hole 22 that is adapted to partially cover the head of the screw bolt 15 and prevent it from moving longitudinally with respect to the bead 12 and the pulley stile. This locking plate is capable of vertical movement and may be pushed up and down readily by means of a tool inserted through the slot 21 into one of the holes 20. Lugs 23 are provided on said plate in position to contact with the bars 14 and limit the downward movement of the plate. A stop 14' limits the vertical movement of the plate 19. When this plate is pushed down to its operative position, as shown in Fig. 3, it will cover the outer portion or rim of the head of the screw bolt, and while the slot in the bolt will be accessible through the hole 22 for a screw driver, the plate cannot move lengthwise with respect to the stile, the rotation of the bolt causing it to move in and out in the bar 16 and adjusting the stile toward or from said bar until the stile has been properly set for the width of the window sash.

The adjustment of the stile is very simple, being easily accessible from the inside or outside of the window and may be used on one or both sides of the window. Its action is positive and when the adjustment is complete and the plate 19 moved to its locking position, it will be impossible for the stile to

move on the bolt or change its position with respect thereto without revolution of the screw.

The pulley stile is preferably a little wider than the combined thickness of both sash, as plainly shown in Fig. 2. This allows the accurate fitting of the sash in the window, even though there may be a variation in width between the top and bottom of the frame due to various causes, or there may be a slight difference in the width of the sash themselves. By providing a stile the full thickness of both sash I can readily obtain the necessary adjustment and fit the sash to slide smoothly in the frame after the frame has been set up in the building wall, and by locating the adjusting means in the parting bead between the sash, I can have easy access to the adjusting means from either side of the window. This I regard as an important feature of my invention.

The bar 16, in addition to its function of supporting the screw 15, strengthens, braces and holds in place the metallic frame of the window and aids materially in its power of resistance to heat. I have shown but one of these bars and screws, but any suitable number of them may be employed, according to the height of the window.

30 I claim as my invention:—

1. A fire-proof window frame including a jamb, a pulley stile, a parting bead thereon, an upper and lower sash, said stile being of greater width than the combined thickness of both sash, a screw fitting within a socket in said parting bead between said upper and lower sash and passing through said stile and into a threaded socket provided in the rear of said stile, said screw being accessible from either side of the window and its lengthwise movement causing said stile to be adjusted toward or from said sash to adapt the window to sash of different width.

45 2. A fire-proof window including a jamb, a pulley-stile, a parting bead thereon, an upper and lower sash, said stile being of greater width than the combined thickness of said sash, a bar secured to said jamb in the rear of said stile and having a threaded socket therein, a screw passing through said bead and stile and into a socket in said bar, the longitudinal movement of said screw adjusting said stile toward or from said sash and adapting the window to sash of different width, and means slidably mounted in said bead and adapted to partially cover the head of said screw and prevent longitudinal movement thereof when revolved in one direction.

55 3. The combination, with a window frame and sash, of a pulley stile composed of flat sheet metal, a parting bead on said stile, means having a threaded socket in the rear 65 of said stile, a screw passing through said

bead and stile into said threaded socket, and a sliding plate arranged to partially conceal the head of said screw and prevent outward movement thereof independently of said head, for the purpose specified.

70 4. The combination, with a window frame and sash, of a pulley stile and means for moving it toward or from said sash, said means including a screw passing through said stile and having a stationary threaded socket in the rear of the same, and a sliding, locking plate having an opening therethrough adapted to partially conceal the head of said screw, for the purpose specified.

75 5. The combination, with a metal window frame and an upper and lower sash therefor, of a pulley stile of greater width than the combined thickness of both sash capable of movement toward or from said sash, a parting bead mounted on said stile between said sash, means mounted in said parting bead and operating to adjust said stile back and forth, toward and from said sash to adapt the window to sash of different width.

80 6. A fire-proof window frame jamb composed of sheet metal having its side portions bent inwardly to form the sash weight pockets, the inner edges of said side portions being bent toward one another, forming guides for the window sash, transverse bars secured to the side portions of said jamb and holding them in parallel relation with one another, and a pulley-stile disposed between said bars and the inwardly turned edges of said side portions.

85 7. A fire-proof window frame jamb composed of a piece of sheet metal having its side portions bent inwardly to form with the middle portion thereof sash weight pockets, the edges of said inwardly turned side portions being bent toward one another at right angles substantially to said side portions, a bar having its ends secured to said side portions and extending transversely of the jamb and bracing and strengthening said side portions, a movable pulley stile having its edges slidable with respect to the edges of said side portions, and a screw passing through said stile and threaded in said cross bar, for the purpose specified.

90 8. A fire-proof window frame jamb consisting of a sheet of metal having its side portions bent inwardly at right angles substantially to the middle portion of the sheet to form the sash weight pockets, the inner edges of said side portions being bent toward one another and terminating in outwardly projecting vertical flanges forming guides for the window sash and transverse bracing means secured to the side portions of said jamb, a pulley stile disposed between said bracing means and the inwardly turned edges of said side portions, an ad-

justing means passing through said stile and into said bracing means and permitting the adjustment of said stile toward and from the window sash.

- 5 9. A fire-proof window-frame composed of sheet metal having its edges folded inwardly to form pockets for the sash weights, a bracing and strengthening bar extending transversely of said frame and rigidly connecting the opposite inwardly turned portions thereof, a pulley-stile interposed between said opposite inwardly turned portions and said bar, and a stile adjusting means engaging said stile and said bar.
- 10 10. The combination, with a metal window-frame and an upper and lower sash, of a pulley-stile of greater width than the combined thickness of said sash and capable of movement toward or from said sash to adapt said frame to sash of different width, strengthening bars for said stile, a stile adjusting means located between said sash and passing through said bars, and means having a socket for said adjusting means 25 in the rear of said stile.
11. The combination, with a metal window-frame and the upper and lower sash therefor, of a pulley-stile of greater width than the combined thickness of both sash, 30 a parting-bead on said stile, a transverse bracing means having a threaded socket in the rear of said stile, an adjusting screw passing through said bead and stile and into said threaded socket, the head of said 35 screw being exposed through an opening in said bead and accessible between said sash.
12. A fire-proof window-frame consisting of a sheet of metal having its side portions bent inwardly at an angle to the middle portion of the sheet to form sash weight pockets, the inner edges of said side portions being bent toward one another and terminating in outwardly projecting flanges 40 forming guides for the window sash, a transverse bracing means secured to the side portions of said frame, a pulley-stile disposed between said bracing means and the inwardly turned edges of said side portions 45 and having a parting bead, an adjusting means engaging said bead and stile and said bracing means for adjusting said stile toward or from the window sash, and means preventing relative movement of said adjusting means and said stile.
- 50 55 13. A fire-proof window-frame jamb composed of sheet metal having its edges folded inwardly to form pockets for the

sash weights, a bracing and strengthening means disposed between said inwardly folded edges, a pulley-stile of sufficient width to form bearing surfaces for the upper and lower sash the full thickness thereof, said stile being movable toward and from the sash and guided in such movement by the inwardly folded edges of said jamb, and means centrally mounted in said stile and engaging said strengthening means and adapted to move said stile toward or from said strengthening means to compensate for varying widths of the window-sash, substantially as described.

14. A fire-proof window frame jamb composed of sheet metal having inwardly turned side portions to form the sash weight pockets, bars rigidly connecting said inwardly turned side portions and holding them in parallel relation with one another, the edges of said inwardly turned side portions being bent toward one another, forming guides for the window sash, a pulley-stile disposed between said inwardly turned edges and said bars, strengthening bars secured to said pulley-stile, and a stile adjusting means having bearings in said strengthening bars and fitting within sockets provided in said brace bars.

15. The combination, with a metal window frame, of a pulley-stile, strengthening bars extending transversely of said pulley-stile, transverse brace bars in the rear of said stile and having sockets therein, and stile adjusting screws having bearings in said strengthening bars and fitting the sockets in said brace bars.

16. A fire-proof window frame jamb composed of sheet metal having its side portions bent inwardly to form the sash pockets, transverse brace bars secured to said side portions and holding them in parallel relation with one another, the ends of said brace bars being bent to form comparatively long bearings on said side portions, the edges of said side portions being bent around the ends of said brace bars and bearing thereon and extending inwardly toward one another and forming guides for the window sash, and a pulley-stile interposed between said inwardly extending edges and said brace bars.

In witness whereof, I have hereunto set my hand this 25th day of May, 1910.
